FURNACE WALL STRUCTURE

George W. Dayve, Worcester, Mass.

Application December 8, 1937, Serial No. 178,762

8 Claims. (Cl. 72—101)

This invention relates to furnace wall structures, and more particularly to structures of the type having an inner wall of refractory material which is sectionally supported by an outer framework. This application is a continuation in part of my prior application Serial No. 121,938, filed January 23, 1937.

It is one object of the invention to provide a furnace construction in which the inner wall is more firmly secured to the outer framework, and yet the individual tile forming the inner wall may be readily removed and replaced when desired.

It is a further object of the invention to provide furnace wall structure so arranged that the individual tile forming the inner wall will remain in their proper positions despite large and heavy accumulations of slag on their inner faces.

With these and other objects in view, as will be apparent to those skilled in the art, the invention resides in the combination of parts set forth in the specification and covered by the claims appended hereto.

Referring to the drawing illustrating one embodiment of the invention and in which like reference numerals indicate like parts,

Fig. 1 is a vertical section showing one form of furnace wall structure;

Fig. 2 is a section on the line 2—2 of Fig. 1, with certain of the inner wall tile broken away;

Fig. 3 is an enlarged view in section on the line 3—3 of Fig. 1;

Fig. 4 is a perspective view of one of the bearing tile shown in Fig. 1; and

Fig. 5 is a view similar to Fig. 1 showing a modified form of the invention.

The embodiment illustrated in Figs. 1 to 4 comprises a row of spaced vertical columns 10 of I-beam section to which are secured a series of vertically spaced horizontal beams 11 in the form of channel members. The webs of the channel members are in contact with the flanges of the columns. A series of horizontally spaced brackets 12 are secured to each of the channel members 11 by means of bolts 14, and these brackets are provided with ribs 15 (Fig. 3) which engage the heads of the bolts and prevent them from turning at assembly. Certain of the brackets 12 may be located directly opposite the columns 10, as shown in Fig. 2, and a pair of bolts may be provided which extend through the bracket, the channel member, and the flanges of the column. To accommodate these two bolts, each bracket may be provided with a pair of horizontally spaced slots 16 (Fig. 3).

The brackets 12 serve to support vertically

spaced horizontal rows of refractory bearing tile 18 and for this purpose each bracket is formed with a pair of vertically spaced flanges 19 which project inwardly at an upward inclination, as shown particularly in Fig. 1. Each bearing tile 18 is of substantially diamond shape cross-section, with upper and lower surfaces which slope inwardly and upwardly, the outer portions of the tile being located and supported between the flanges 19. As shown in Fig. 2, each bearing tile 18 is preferably of sufficient length, in a direction parallel to the beam 11, to engage two of the brackets 12. The bearing tile are preferably secured to the brackets, and for this purpose each tile may have a pair of holes 20 extending vertically therethrough (Fig. 4), and vertical pins 21 may be inserted through these holes at assembly, these pins also passing through aligned holes in the flanges 19, as indicated in Fig. 1.

The bearing tile 18 provide means for sectionally supporting an inner refractory wall 23 having its inner or heat-exposed face spaced inwardly beyond the inner ends of the bearing tile, so that these bearing tile are separated from the furnace chamber by a substantial thickness of refractory material. The outer face of the wall 23 is located near the inner ends of the bracket flanges 19, the bearing tile 18 extending inwardly for a considerable distance into the wall 23 and preferably somewhat beyond the center thereof. The wall is grooved or recessed to receive the bearing tile. This inner wall 23 is constructed of refractory wall tile arranged in horizontal rows, and in the embodiment shown in Fig. 1 there is one row of wall tile 25 for each row of bearing tile 18. These wall tile are generally diamond shape in cross-section, with recesses 26 in their outer corners to receive the bearing tile, and their weight is supported by the bearing tile therebeneath. A slight clearance space is shown between each row of wall tile and the tile thereabove, and this space may be filled at assembly with suitable refractory packing material 27.

The bearing tile preferably extend inwardly for an appreciable distance beyond the centers of gravity of the wall tile, so that the wall tile will be held by gravity in the proper position. If however, a heavy coating of slag should adhere to the inner face of the wall 23, there might be a tendency for the wall tile to tip inward toward the furnace. In order to avoid this possibility I provide means for securing the wall tile to the bearing tile thereabove. This is preferably accomplished by forming the wall tile and the bearing tile with interfitting parts, and in

Fig. 1 each of the bearing tile 18 is provided with a depending rib 29 on its lower surface which at assembly fits within a cooperating groove 30 in the upper surface of the wall tile 25. The rib 29 is spaced outwardly a short distance from the inner face of the bearing tile, and the lower surface of the rib is semi-cylindrical, the groove 30 being correspondingly shaped. It will be clear that by reason of the engagement of the rib 29 with the groove 30, and the securing of the bearing tile 18 to the brackets 12, inward tipping of the wall tile 25 is effectually prevented.

In order to facilitate insertion and removal of the wall tile without disturbing the bearing tile, the rib 29 may be interrupted, as shown in Fig. 4, to leave a gap 32 having a width slightly greater than the thickness of the wall tile. The wall tile can be inserted through this gap and then moved laterally along the rib. Preferably, when the assembly is complete the joint between two adjacent wall tile will be in line with the gap, so that all the wall tile will be locked in place. Obviously the gap 32 need not be located intermediate the ends of the rib 29, but may be formed by omitting a portion of the rib at one or both ends thereof.

In Fig. 5 certain modifications of the invention are illustrated. This embodiment comprises a row of spaced vertical columns 34, and channel members 35 secured thereto, these parts being similar to the corresponding parts shown in Fig. 1. The channel members 35 are however spaced apart vertically a somewhat greater distance than the channel members 11 in Fig. 1. Horizontally spaced brackets 36 are fastened to the channel members 35 by means of bolts 38, and each bracket is formed with a pair of vertically spaced flanges 39 which slope upwardly and inwardly. Refractory bearing tile 40, generally diamond shaped in cross-section, are supported by the brackets 36, and these bearing tile provide means to sectionally support an inner refractory wall 42. The bearing tile 40 are secured to the brackets 36, and for this purpose each upper flange 39 is provided on its lower surface with a transverse semi-circular groove 43 and each bearing tile is provided on its upper surface with a transverse semi-circular groove 44. At assembly the grooves 43 and 44 form a circular opening into which a short rod 45 is inserted to lock the parts together.

The inner wall 42 is constructed of refractory wall tile arranged in horizontal rows, each row of bearing tile 40 serving to support a lower row of wall tile 47 and an upper row of wall tile 48. The wall tile 47 and 48 are generally diamond shape in cross-section, with recesses to receive the bearing tile. As shown, each lower wall tile 47 has a recess 49 in its lower outer corner, and each upper wall tile 48 has a recess 50 in its upper outer corner, these recesses being sufficiently deep to allow the bearing tile to extend inwardly beyond the centers of gravity of the wall tile. A slight clearance space is provided between each row of wall tile 48 and the tile thereabove, and this space may be filled at assembly with suitable refractory packing material 52.

In order to prevent inward tipping of the wall tile in the event of excessive accumulations of slag on the inner face of the wall, a rib 53 is provided on the lower surface of each bearing tile 40. This rib is diamond shape in cross-section and is located adjacent the inner face of the bearing tile. At assembly the rib 53 fits within

a similarly shaped transverse groove 54 formed in the upper surface of the wall tile 48. The rib 53 need not be interrupted, as was the rib 29 in Fig. 4, since the wall tile 48 can be inserted from beneath the rib, and the wall tile 47 can then be inserted beneath the tile 48. With this construction the tile 48 are locked to the bearing tile, and the tile 47 are held in place not only by their own weight but also by the weight of the tile 48 resting on them.

It will now be apparent that the invention provides an inner refractory wall formed of wall tile and sectionally supported by means of bearing tile which are protected from the furnace heat by the wall tile. The bearing tile are supported by a metal framework which is located entirely outside of the refractory wall. The bearing tile are secured to the framework to prevent them from moving inwardly, and the wall tile in turn are secured to the bearing tile to prevent inward tipping of the wall tile. The wall tile can readily be removed and replaced without disturbing the bearing tile. The entire construction is comparatively simple and inexpensive.

Having thus described my invention, what I claim as new and desire to secure by Letters Patent is:

1. A furnace wall structure comprising an outer framework, vertically spaced horizontal rows of refractory bearing tile mounted on the framework and projecting inwardly therefrom, the bearing tile being secured to the framework to prevent them from moving inwardly, and horizontal rows of refractory wall tile supported by the bearing tile to form an inner wall and having portions disposed between the bearing tile and the inner face of the wall to protect the bearing tile from the furnace heat, the bearing tile being secured to the wall tile therebeneath to prevent inward tipping thereof.

2. A furnace wall structure comprising an outer framework, vertically spaced horizontal rows of refractory bearing tile mounted on the framework and projecting inwardly therefrom, the bearing tile being secured to the framework to prevent them from moving inwardly, and horizontal rows of refractory wall tile supported by the bearing tile to form an inner wall and having portions disposed between the bearing tile and the inner face of the wall to protect the bearing tile from the furnace heat, the bearing tile and the wall tile therebeneath having interfitting parts shaped and arranged to prevent inward tipping of the wall tile.

3. A furnace wall structure comprising an outer framework, vertically spaced horizontal rows of refractory bearing tile mounted on the framework and projecting inwardly therefrom, the bearing tile being secured to the framework to prevent them from moving inwardly, and horizontal rows of refractory wall tile supported by the bearing tile to form an inner wall and having portions disposed between the bearing tile and the inner face of the wall to protect the bearing tile from the furnace heat, each bearing tile having a rib on its lower surface arranged to project into a transverse groove in the upper surface of the wall tile therebeneath to prevent inward tipping of the wall tile.

4. A furnace wall structure comprising an outer framework, vertically spaced horizontal rows of refractory bearing tile mounted on the framework and projecting inwardly therefrom, the bearing tile being secured to the framework to prevent them from moving inwardly, and hori-

zontal rows of refractory wall tile supported by the bearing tile to form an inner wall and having portions disposed between the bearing tile and the inner face of the wall to protect the bearing tile from the furnace heat, each bearing tile having a rib on its lower surface arranged to project into a transverse groove in the upper surface of the wall tile therebeneath to prevent inward tipping of the wall tile, the rib being interrupted to provide a gap through which the wall tile may be inserted without disturbing the bearing tile.

5. A furnace wall structure comprising an outer framework, vertically spaced horizontal rows of refractory bearing tile mounted on the framework and projecting inwardly therefrom, the bearing tile being secured to the framework to prevent them from moving inwardly, and two horizontal rows of refractory wall tile supported by each row of bearing tile to form an inner refractory wall 10 having portions disposed between the bearing tile and the inner face of the wall to protect the bearing tile from the furnace heat, the bearing tile and the wall tile therebeneath having interfitting parts shaped and arranged to prevent inward 15 tipping of the wall tile.

6. A furnace wall structure comprising an outer framework, vertically spaced horizontal rows of refractory bearing tile mounted on the framework

and sloping upwardly and inwardly therefrom, the bearing tile being secured to the framework to prevent them from moving inwardly, horizontal rows of refractory wall tile supported by the bearing tile to form an inner wall, the wall tile being substantially diamond shape in cross-section and having portions disposed between the bearing tile and the inner face of the wall to protect the inner faces of the bearing tile from the furnace heat, and means securing the bearing tile to the wall tile therebeneath to prevent inward tipping of the wall tile.

7. A bearing tile for a furnace wall structure comprising a block of refractory material substantially diamond shape in cross-section and having provision near its outer edge for securing it to a supporting framework, and a rib on the lower surface of the block near its inner edge.

8. A wall tile for a furnace wall structure comprising a block of refractory material substantially diamond shape in cross-section, with upwardly and inwardly inclined top and bottom surfaces, and a transverse groove in the upper surface of the block, the block having a portion projecting upwardly from its upper inner corner and a portion projecting downwardly from its lower inner corner.
